US0D1071899S

(12) **United States Design Patent** (10) Patent No.: **US D1,071,899 S**
(45) Date of Patent: ** Apr. 22, 2025

(54) **HEADSET**

(71) Applicant: **Lijun Xie**, Hubei (CN)

(72) Inventor: **Lijun Xie**, Hubei (CN)

(**) Term: **15 Years**

(21) Appl. No.: **29/874,102**

(22) Filed: **Apr. 14, 2023**

(30) **Foreign Application Priority Data**

Mar. 9, 2023 (CN) 202330105639.6

(51) LOC (15) Cl. **14-01**

(52) U.S. Cl.

USPC **D14/206**; D14/226

(58) **Field of Classification Search**

USPC D14/206, 226, 205, 225; D24/174;

128/864-866; 381/380-381, 374, 375

Primary Examiner — Paula Allen Greene

(57) **CLAIM**

The ornamental design for a headset, as shown and described.

DESCRIPTION

FIG. 1 is a right side, top perspective view of a headset, showing my new design;

FIG. 2 is a left side, bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the figures illustrate portions of the article that form no part of the claimed design.

1 Claim, 8 Drawing Sheets
